UNITED STATES PATENT OFFICE.

JOHN WILSON MCKINNEY, OF GROESBECK, TEXAS.

WIRE-STRETCHER.

SPECIFICATION forming part of Letters Patent No. 499,307, dated June 13, 1893.

Application filed April 20, 1893. Serial No. 471,112. (No model.)

To all whom it may concern:

Be it known that I, JOHN WILSON MCKINNEY, a citizen of the United States, residing at Groesbeck, in the county of Limestone and 5 State of Texas, have invented a new and useful Wire-Stretcher, of which the following is a specification.

The invention relates to improvements in wire stretchers.

The object of the present invention is to provide a simple and efficient device adapted for stretching wire for fence-building, for tightening loose wires, for cutting wires, and for tying broken wires of a fence in a tight 15 and efficient manner.

The invention consists in the construction and novel combination and arrangement of parts hereinafter fully described, illustrated in the accompanying drawings, and pointed 20 out in the claims hereto appended.

In the drawings: Figure 1 is a perspective view of a wire stretcher constructed in accordance with this invention. Fig. 2 is a detail perspective view of one of the members. 25 Fig. 3 is a plan view, showing the members arranged for cutting wire.

Like numerals of reference indicate like parts in all the figures of the drawings.

1, 1, designate similar members, pivotally 30 connected by a bolt 2, and each consisting of a disk 3, a curved jaw 4, and a shank 5, to which is secured a handle-bar 6. The disks have central registering openings to receive the bolt 2, which is provided with a rectangular head having a wire-receiving notch 7. The jaws 4 are similarly curved, being approximately semicircular, and are provided 35 at their outer ends with claws formed by recesses 8, and they are provided with similar oppositely-disposed circular notches 9. The disks are provided with registering notches 10, and when it is desired to sever a wire the notches 10 are made to register, the wire is placed therein, and the notches are then 40 turned away from each other, thereby cutting the wire.

When it is desired to stretch a fence-wire, a fence-post is grasped by the jaws of the stretcher and the wire is placed in the recess 45 of the head of the bolt. The wire is then twisted and drawn around the post by moving the stretcher around the latter, and when the wire is at the desired tension it is stapled.

In tying a broken-wire, the ends of the wire are placed in the claws of the jaws, when the latter are open, and are held therein by placing a barb in the notch 9 of each jaw. The jaws are then brought together to stretch the wire which is tied by twisting the stretcher in either direction. If there are no barbs at 60 the ends of the wire, the latter is bent or knotted to form stops to prevent the wire from being drawn through the notches 9.

It will be seen that the wire stretcher is simple and inexpensive in construction and 65 efficient in operation, and that it is adapted for stretching, tying, and cutting wire.

Changes in the form, proportion, and the minor details of construction may be resorted to without departing from the principle or 70 sacrificing any of the advantages of this invention.

The wire stretcher is also adapted for drawing staples; and to accomplish this result the claw is inserted under a fence-wire and made 75 to straddle a staple, and by turning the curved jaw using it as a heel or fulcrum, the staple may be readily drawn out of the fence post.

What I claim is—

1. A wire stretcher comprising the similar 80 members provided with jaws, and a pivot-bolt provided with an enlarged head having a wire-receiving recess, substantially as described.

2. A wire stretcher comprising similar pivoted members provided with jaws having 85 claws at their outer ends and provided adjacent to the claws with opposite wire-receiving recesses, substantially as described.

3. A wire stretcher comprising similar members consisting of shanks and curved jaws 90 provided with claws and having opposite wire-receiving notches, a pivot-bolt connecting the members and having a rectangular head provided with a wire-receiving recess, and handle-bars secured to the shank, substantially 95 as described.

In testimony that I claim the foregoing as my own I have hereto affixed my signature in the presence of two witnesses.

JOHN WILSON MCKINNEY.
